UNITED STATES PATENT OFFICE.

SUSAN B. PARKER, OF ARLINGTON, MASSACHUSETTS.

COIL SAFETY PIN.

1,413,423.

Specification of Letters Patent. Patented Apr. 18, 1922.

Application filed August 6, 1921. Serial No. 490,201.

To all whom it may concern:

Be it known that I, SUSAN B. PARKER, a citizen of the United States, residing at Arlington, in the county of Middlesex and State of Massachusetts, have invented certain new and useful Improvements in Coil Safety Pin, of which the following is a specification.

This invention relates to safety pins of a well known form, wherein a single length of spring wire is coiled upon itself at its mid-length, and has one end sharpened and adapted to engage and be shielded by the other end of the wire. I have observed that when an extra heavy strain comes upon the clothing fastened together by this pin, the pin-portion receives a permanent bend which not only badly affects the appearance thereof, but renders the pin-point liable to withdrawal from the shielded end and thereby to fail in its attaching function.

The main cause for such bending of the pin I find to be due to the unyielding action of the shield-carrying portion of the device, the same being so inflexible as to force all the flexure to be performed by the pin-section alone.

To remedy this, I have devised means for rendering the shielding section of the safety pin quite flexible, this being preferably done by forming the section with several helical coils, the same being bent over to lie nearer to a common plane in order to keep the safety pin as thin as possible. While I have invented other means for giving the desired flexibility, as by flattening the shielding section to lie in a plane at right angles to the plane of the two pin-sections, or by giving the wire numerous zig-zag bends, yet the preferred arrangement appears to give the best results, and at the same time provides a convenient means for stitching the safety pin to a garment when so desired.

In the drawings forming part of this specification, Fig. 1 is a side view on an enlarged scale, of a safety pin embodying my improvements. Fig. 2 is a top view of the same. Fig. 3 illustrates a modification of the shielding pin portion. Fig. 4 is another modification.

As shown in Fig. 1, the safety pin consists of a length of spring wire bent at its mid-length to form a coil 1, and having its pin section 2 sharpened in the usual way and engaging the shield 3 held by the other portion 4 of the wire. 55

The portion 4 of the wire is formed with several coils 5, preferably made helical and then bent over to lie one against the other, as illustrated in Fig. 2. Thus made, the back 4 is rendered sufficiently flexible to relieve the bending strain otherwise put upon the pin section 2. 60

In addition to this flexibility given to the back 4, the coils 5 provide eyes through which to pass stitches into a fabric to which it may be desired to attach the pin. These eyes being located at the midlength of the back 4 and of the safety pin, the stitches through the same will properly balance the pin in its suspension action. 65 70

In the construction illustrated in Fig. 3, the back 4' is seen to be flattened for giving it the flexibility desired. While this requires less wire for its manufacture, it does not provide the eyes suitable for stitching the pin to a fabric. 75

While the zig-zag bends 6 shown in Fig. 4 provide a limited flexibility to the back 4'', it is insufficient for the purpose, and the sharpness of the bends render the same liable to fracture.

What I claim is:

A safety pin comprising a length of wire bent at substantially its midlength to form two resiliently related sections one of which is sharpened, and the end of the other being constructed to laterally receive said sharpened end, the last-named section being bent to compose a series of helical coils flattened one against another to permit the pin to occupy a minimum of space, whereby said coils not only give flexibility to the last-named section but also provide eyes by means of which the pin can be stitched to any fabric. 90 95

In testimony that I claim the foregoing invention, I have hereunto set my hand this 4th day of August, 1921.

SUSAN B. PARKER.
